UNITED STATES PATENT OFFICE.

JAMES W. HUDSON, OF SAN FRANCISCO, CALIFORNIA.

LICENSE-DISPLAY TAG.

1,293,099.

Specification of Letters Patent.

Patented Feb. 4, 1919.

Application filed June 10, 1915. Serial No. 33,268.

To all whom it may concern:

Be it known that I, JAMES W. HUDSON, a citizen of the United States, residing at San Francisco, in the county of San Francisco and State of California, have invented 5 certain new and useful Improvements in License-Display Tags, of which the following is a specification.

My invention relates to the class of card, 10 picture, and sign exhibiting, and more particularly to a new and improved license display tag.

The primary object of my invention is to provide a license display tag capable of 15 continuous use from year to year without the necessity of obtaining a new tag every time the license is renewed, license in this particular instance pertaining to automobile 20 licenses.

Another object of my invention is to provide a license display tag which is simple in construction, cheap to manufacture, strong and durable, and one which is easily and 25 quickly assembled for use.

With the above and other objects in view 30 my invention resides preferably in the construction, combination and arrangement of parts as hereinafter set forth in the specification and illustrated in the accompanying drawings, in which—

Figure 1 is a perspective view of a license displaying tag embodying the preferred form of my invention.

Fig. 2 is a longitudinal sectional view of 35 a display tag taken on the longitudinal axis thereof.

Fig. 3 is a front elevation of my improved tag without the date plate, and

Fig. 4 is a perspective view of the date 40 plate which I employ in the preferred embodiment of my invention.

Similar reference characters indicate similar parts throughout the various views of the drawing.

It is a well known fact to those familiar 45 with the usual form of license tag that the whole tag must be removed and replaced by a new tag when the license is renewed from year to year. It is an object, together with 50 the foregoing to obviate the necessity of the renewal of the entire tag, it being possible in this form of tag to build the same integral with the body of an automobile or integral with the head lights, or some such conspicuous point.

I have provided a main plate 1 on which the license number 2 and the territorial designation 3 is placed. The plate 1 is provided with a plurality of elongated apertures 4 adjacent one extremity thereof for a purpose which will hereinafter appear. 60

A supplemental date plate is provided and designated 5, said date plate having a license number 6 corresponding to the license number 2 and the date of the year for which the 65 license is granted designated 7 thereon. A plurality of bendable tongues 8 are provided on the end and side marginal edges of the plate 5 and are complementally disposed for engagement in the apertures 4 70 formed in the plate 1. The mounting of the date plate 5 on the main plate 1 is shown to advantage in Fig. 2, wherein the tongues 8 are inserted through the apertures 4 and bent down upon the plate 1, serving to secure the date plate 5 thereon. 75

From the above description taken in connection with the accompanying drawings it is thought that a clear and comprehensive understanding of the construction, use, and 80 advantages of my invention may be gathered. It will be noted that the complete renewal of the main plate 1 is unnecessary and that the renewal of the plate 5 may be accomplished by straightening the tongues 8 to 85 allow of detachment of the plates 1 and 5, whereupon a new plate having a new date thereon may be attached. It will also be noted that, as stated hereinbefore, the main plate 1 may be easily formed as the side wall 90 of a headlight, rear light, or the like, of course, it being understood that the same is placed in some conspicuous place on an automobile.

While I have shown and described my invention as possessing a peculiar form and construction, it is desired that it be understood that I may make such changes in the details thereof that do not depart from the spirit and scope of the invention as claimed. 95

Having thus described my invention, what I claim and desire to secure by Letters Patent is:

1. The combination with a number plate having upon it numerals forming a permanent number and a separate space, of a detachable yearly license slip adapted to be attached to the number plate at said space and having upon it numerals forming the same number as that on the permanent number 105 110

plate, whereby such slip will be identified with the number of the car and cannot be used with another number plate.

2. The combination with a plate having upon it a permanent indicia and a separate space, of a detachable yearly license slip adapted to be attached to the plate at said space and having upon it indicia corresponding with the indicia of said plate whereby

the slip will be identified with the permanent 10 indicia of the plate.

In testimony whereof I affix my signature in presence of two witnesses.

JAMES W. HUDSON.
